United States Patent

Des. 236,000
Patented July 22, 1975

236,000

BATHTUB

David Harman Powell, Maldon, England, assignor to Pye Limited

Filed Jan. 28, 1974, Ser. No. 437,512

Claims priority, application Great Britain July 26, 1973

Term of patent 14 years

Int. Cl. D23—02

U.S. Cl. D23—48

FIG. 1.

FIG. 2.

FIG. 3.

FIG. 4.

FIG. 5.

FIG. 1 is a perspective view taken from one end of a bathtub showing my new design;

FIG. 2 is a top plan view thereof;

FIG. 3 is a perspective view taken from the end opposite that shown in FIG. 1;

FIG. 4 is a side elevational view thereof; and

FIG. 5 is a cross sectional view taken on line V—V of FIG. 2.

I claim:

The ornamental design for a bathtub, substantially as shown.
